OSCILLATING VANED PISTON PUMP

Benjamin Phillips, Cincinnati, Ohio

Application December 12, 1945, Serial No. 634,445

14 Claims. (Cl. 103—145)

1

This invention relates to pumps and is particularly directed to a pump of the double acting oscillating type. This particular type of pump is effective for intake and delivery in both strokes.

In the past, pumps of this type have been made of castings and these castings have required expensive casting and finishing operations to produce the necessary passageway ports and valve openings.

It has been the object of the present inventor to provide a pump of this type which is made principally of stamped or pressed sheet metal parts. Particularly, the present inventor has improved the art in that he has constructed the main valve and port element, which in the present construction constitutes the baffle, to include a pair of pressed sheet metal elements which elements are duplicates and which, when assembled, provide a symmetrical structure in cross-section. Prior to the forming of these elements to make up the baffle and port arrangement, they are punched to provide the necessary valve ports and passageways.

A novel feature of the construction resides in the construction of the central portion of the baffle through which the pumped medium is permitted to flow between the chambers for ejection and intake purposes. This central chamber is divided by a partition which is easily incorporated and which permits alternate flow in reverse directions as the pumping element is moved relative to this assembly. The pumping vane and drum assembly which is the actuator or impeller is also constituted of sheet metal parts and is designed to fit snugly within the pump casing. The casing is cup-shaped with the intake and outlet openings entering its closed end. The drum carrying the actuator vane is open at one end and is nested in the pump casing with its open end disposed against and within the closed end of the casing. Therefore, a simple external seal ring may be used for holding these elements in nested arrangement and providing the necessary seal.

It has been a further object of the present inventor to provide a novel arrangement of the pump elements particularly with a view to improvement and simplification of the sealing means, as well as the assembly. To accomplish this purpose, a structure has been provided in which the ports and valves for controlling the flow are located in a stationary baffle or wall which is fixed in relation to the inlet and outlet passageways. The impeller or actuator consists of a cup-shaped element and a diametric vane

2

fixed therein. This actuator is assembled relative to the baffle so that the stationary baffle is diametrically disposed therein and the entire assembly is surrounded by a pump casing. Thus, it will be obvious that seals are necessary only for the rotative contact between the stationary baffle and the cup-shaped element of the actuator and between the vanes of the actuator and the central portion of the stationary baffle.

10 Further, the stationary baffle and port unit is easily removably inserted into fixed position relative to intake and outlet projections. Actually, the first step in the assembly is to place the cup-shaped actuator element, carrying the vane within the pump casing. The port and baffle unit has been assembled in position in this actuator element and upon insertion into the pump casing is engaged in fixed relationship to the passageways of the manifold element.

20 A still further object of the present inventor has been the provision of an improved pump structure which is highly suitable for pumping edible fluids in that it is readily assembled and disassembled which feature is of great importance in that cleaning of the parts may be frequently and readily accomplished. Also, the usual packing glands which may cause contamination of edible fluids are eliminated due to the fact that the operating handle is connected to the outside 25 of a rotatable drum and vane assembly which serves as the actuating or impelling means, no shaft being required for the crank or pumping handle. The sheet material used lends itself easily to plating and stainless steel or aluminum sheets may be used in the fabrication of the parts.

30 Another advantage in the structure is the use of a metal to metal seal between the drum and vane unit and the pump casing. The cup-shaped element or drum of the unit has its open end in contact with the inner wall of the pump casing as these parts are nested together with the result that the seal becomes more effective as use continues due to a lapping in action constantly tending to more perfectly seat the parts at the contact area.

35 Additional features of novelty reside in the structure of the seals between the rotating drum and vane unit and the stationary port and baffle assembly.

40 Other objects and advantages of the invention will be more fully apparent from the description of the drawings, in which:

45 Figure 1 is a perspective view of the assembled pump.

50 Figure 2 is a sectional view taken diametrically

of the pump and showing the intake and outlet ports in relation to the port and baffle assembly.

Figure 3 is a sectional view taken on line 3-3 (Figure 2) showing the pump actuating member at the completion of the pumping stroke in one direction with the valves in appropriate positions.

Figure 4 is a sectional view taken on line 4-4 (Figure 2) showing the pump actuating element at the completion of the stroke in the opposite direction from that of Figure 3 with the valves in appropriate positions.

Figure 5 is an enlarged fragmentary sectional view of a portion of Figure 2 detailing the sealing ring in conjunction with the assembly ring for the pump body.

Figure 6 is a fragmentary enlarged sectional view taken from Figure 3 and illustrating the seal between the port and baffle assembly and the vane of the pump actuator.

Figure 7 is a view taken similar to Figure 6, 20 but showing a modified type of seal.

Figure 8 is a developed view of one of the baffle plates showing the valve ports and the ports connecting the respective chambers of the pump.

Described in general, the pump includes a fixed manifold coupling element, a port and baffle assembly fixed with respect to the manifold coupling element, a pump casing surrounding the port and baffle assembly and, actuator means consisting of a drum and vane unit. This latter member also includes a handle for manipulation. The pump, as stated, is of the double-action oscillating type, the respective strokes of each oscillation being effective both for intake and delivery.

Referring to the drawings, the manifold element is generally indicated at 10 and constitutes the fixed or base portion of the pump. This element includes an intake passageway 11 and an outlet passageway 12. The openings for these passageways are screw threaded internally adapting the same for attachment to the conduits which supply and deliver the liquid. These passageways enter the face or pump attachment side of the element perpendicularly thereto. The inner ends are also internally screw threaded.

The pump casing 13, also fixed, is secured to the manifold element by means of tubular attachment elements 14. These elements include head portions 15 diametrically slotted for receiving a tool and externally screw threaded shank portions 16. The casing is cup-shaped and its bottom, or closure, wall 17 lies against the manifold element. The attachment elements 14-14 are engaged into the screw threaded inner ends of the passageways through apertures 18 in the wall 17 of the casing. Sealing gasket elements 19 encircle the attachment members between the manifold element and the pump casing.

The impeller, or actuator, members of the pump, indicated at 20, include a drum or cup member 21 and radially inwardly disposed vanes 22. This element 20 is nested within the casing and its open end is disposed inwardly. Thus, a rotative bearing is provided between the impeller or pumping unit and the pump casing. As shown in Figure 2, the inner end of the cup-shaped member 21 engages the inner wall of the pump casing 13 and forms a metal to metal seal. This seal becomes more effective as use continues since the sliding contact surfaces are lapped into a more perfect sealing contact.

The pump casing includes an external flange 23. A sealing ring 24 is provided and is attached to this flange 23 by means of bolts 25 and nuts 26, the bolts passing through the ring and the

flange. The sealing ring includes an angular lip 27 overhanging the marginal edge of the flange 23 for centering the ring on the pump casing. The flange is of sufficient radial width to overhang the outer face of the impeller drum and includes an inwardly turned lip 28. The material at the intersection of the casing side wall and the flange is pressed inwardly to form a clearance. Adjacent this, the material of the clamping ring is provided with a circular indentation 30 which tends to press a portion of the interposed ring gasket 31 into the clearance 29. Thus, the gasket is locked in position and upon tightening of the nuts 26 a seal is provided between the flange and the ring whereas the impeller drum is free to rotate in contact with the packing or ring gasket.

The impeller is actuated by means of a handle 32 which is of yoke form including a handle grip member 33 and attaching arms 34-34 straddling the manifold member and the pump impeller drum. These arms are concentrically attached. The attachment to the manifold element is rotative. For this purpose, a screw element 35 is threaded into the manifold element, the screw including a plain counter-turned portion 36, the shoulder of which abuts the manifold. This counter-turned portion loosely traverses an aperture in the arm. The other arm of the handle is fixed to the impeller drum over a square or irregular hub extension 37, the bore in the arm conforming to the shape of the hub. A washer 38 overhangs the margin of the arm about the aperture and is fixed to the hub by means of a nut and screw 39. Thus, the pump is oscillated by a swinging motion of the handle in strokes of limited length.

Referring again to the vanes 22, particularly Figures 3 and 4, it will be noted that these vanes are made up of identically formed plates or sheet metal members 40. Inasmuch as the vanes are duplicates, the description will be limited to one. Each sheet metal or plate section is formed to provide a radially disposed portion 41, a circumferentially disposed outer attaching flange 42 and an inner seal mounting and stop element at the inner end constituted by a specially formed flange 43. This flange includes a portion turned at right angles to the body of the plate element 41 and a continuation inwardly parallel to the body portion and, finally, a circumferentially turned slotted portion, the end of which constitutes the stop 44 for limiting the oscillatory motion of the impeller.

Thus, it will be seen that when these correspondingly formed plates are assembled face to face with the flanges extending oppositely, a seal receiving groove is formed parallel with the axis of rotation of the impeller. The sealing element, of which two forms have been disclosed, adapted to fit in this longitudinal groove, will be fully described in connection with the relationship of the impeller to the port and baffle assembly.

The port and baffle assembly is also fixed with respect to the manifold and the pump casing, although it is a removable assembly easily placed in position and easily removed in the event of difficulty with the valves or seals. Just as in the case of the vanes, this assembly indicated at 45 is made up of identically formed plate sections which are indicated at 46-46. Each of the plate sections 46 is originally, while in flat condition, punched out to provide ports 47 and 48 and valve openings 49 and 50 (see Figure 8). Likewise, tapped holes 51 are provided at the

respective ends of the valve openings into which holes the valve mounting studs 52 are secured.

After all these openings are formed, the plate element is pressed to a prescribed shape. The intermediate or central portion is pressed to a semi-circular contour 53. At each side of this central portion the metal extends outwardly to provide radially disposed faces which abut (Figure 3) when the elements are assembled. Beyond these flat radial sections 54 the metal is turned outwardly at right angles to provide flat valve seating portions or lands 55 at the areas of the valve openings. From these lands the metal is formed irregularly but generally arcuate so as to encircle the heads 15 of the attaching members 14. The adjacent ends of the arcuate portions do not meet, but a space is left forming a slot 56 within which the sealing members are secured. Just as in the case of the vanes, these members are secured together by seam welding the flat abutting areas.

Thus, the port and baffle assembly is held against rotation due to the fact that the tubular outer sections engage over the heads of the attaching elements 14. The forming of the members places the ports 47 and 48 within the cylindrical central portion of the baffle and the valve openings 49 and 50 within the tubular outer sections of the baffle. In the case of the discharge tubular portion of the baffle, that is, the upper one in the drawings, the valves are internally located. The valves indicated at 51 consist merely of elongated plate members resting by gravity upon the margins of the valve openings. They are held against displacement by means of the attaching studs 52, there being appropriate clearance between the heads of the studs and the lands to permit opening. In the case of the intake valves 58, the lower ones in the drawings, these are externally located and are identical in structure to those of the outlet.

The cylindrical central portion of the port and baffle assembly is divided by a septum 59 disposed diametrically intermediate of the length of the central portion. This septum includes an attaching flange 59a welded to the internal wall of the cylindrical portion. Thus, the ports 47-47 connect across one end of the cylindrical portion and the ports 48-48 across the other end.

Thus, it will be observed that the spaces at both sides of the pump chamber are being filled and discharged at the same time as each stroke is performed. This will be made clear at a later point in a description of the pumping operation.

Sealing between the stationary port and baffle assembly and the drum and vane assembly is accomplished by means of thin sheet metal elements, preferably of phosphor bronze or the like. In the case of the seals between the vanes and the central hub of the baffle, these members consist of longitudinal U-shaped elements 60, the body of which fits in the longitudinal slots and the arms of which spread out laterally beyond the vane where they are provided with cuffs 61 in spring engagement with the circular hub of the baffle. The sealing elements 62-62 between the outer ends of the baffle and inner wall of the drum are of somewhat the same shape except that the arms are more extended and therefore have greater springiness. As shown in Figure 7, the thin sheet metal sealing elements may be replaced by rubber sealing blocks 63.

Describing the operation of the pump, it is pointed out that Figure 3 shows the impeller at the completion of a delivery intake stroke in one

direction; that is to say, the stops 44 of the impeller have engaged the baffle and the intake and outlet valves are still open. As the impeller is rotated counter-clockwise from the position as it appears in this view, alternate valves will open; that is to say, the valves at the right hand side of the view, both intake and outlet, will open. This then constitutes the chambers just ahead of the vanes as the discharge chambers. Since the left hand lower intake valve then closes and the upper right hand outlet valve opens, it is obvious that the liquid will be evacuated ahead of both vanes and will be delivered out through the outlet 42. At the same time, the oil will be drawn in through the inlet through the open lower right hand intake valve and will pass into both areas back of the vanes filling them up for the next stroke. Completion of this stroke is shown in Figure 4 where the stops of the vanes have again come to rest against the baffle. Thus, the pump is fully charged on each stroke and is immediately ready for the return movement of the oscillation.

It will be noted that as the vanes move in the direction shown in Figure 3, the pumped fluid passes from the lower chamber through the ports 47-47 diametrically of the tubular hub portion 53 to the upper chamber and thence into the upper tubular outer discharge portion and out through the outlet passage 42. While this is occurring, the fluid is being drawn in from the inlet 45 into the lower left hand chamber and then through ports 48-48 diametrically through the tubular hub portion 53 to fill the upper right hand chamber. When the rotation is reversed, although the fluid passes in the same direction through the ports 47-47 and 48-48, the chambers (considering the spaces on the opposite sides of the vanes as variable chambers) reverse as to intake and discharge functions.

It will be observed that all the elements of the pump, with the exception of the manifold, are pressed or stamped elements. The sealing of the pump is greatly simplified due to the fact that the ports are contained in the baffle which is stationary and the vane and drum elements making up the impeller are movable. This latter assembly is easily removably nested within the pump casing. The fixed port and baffle unit is assembled merely by slipping it in and out of position in relation to the fixed manifold and pump casing.

Having described my invention, I claim:

1. A pump comprising; a stationary manifold element including inlet and outlet openings, a cup-shaped pump casing fixed in relation to said manifold element, a baffle and port unit fixed in relation to said manifold element and said pump casing, an actuator including a cup-shaped member nested within the pump casing with its open end disposed inwardly, said cup-shaped member including diametrically disposed vanes in a plane bisecting the plane of said port and baffle unit and providing respective pairs of fluid displacement chambers, said port and baffle unit including a pair of passageways connecting alternate displacement chambers in common, and respective check valves controlling flow of fluid relative to each of said displacement chambers, said check valves communicating in pairs with the respective inlet and outlet openings, one of said check valves being arranged to permit passage of fluid outwardly and the other permitting intake of fluid, means for actuating said cup-shaped member in alternate directions, and said

respective sets of alternate displacement chambers operating alternately in common as intake and discharge chambers as said cup-shaped member is actuated in alternate directions.

2. A pump comprising; a stationary manifold element including inlet and outlet openings, a cup-shaped pump casing fixed in relation to said manifold element, a baffle and port unit fixed in relation to said manifold element and said pump casing, an actuator including a cup-shaped member nested within the pump casing with its open end disposed inwardly, said cup-shaped member including diametrically disposed vanes in a plane bisecting the plane of said port and baffle unit and providing respective pairs of fluid displacement chambers, means for oscillating said cup-shaped member and vanes, means for sealing the vanes in relation to the port and baffle unit, ports in said port and baffle unit connecting alternate displacement chambers in common, a sealing ring secured to the pump casing and overlying the outer wall of the cup-shaped member, and respective intake and outlet valves controlling flow of fluid relative to said displacement chambers and said respective inlet and outlet openings.

3. A fluid pump comprising; a pump casing, a double wall baffle disposed diametrically within said pump casing and providing a pair of fluid chambers, impeller vanes disposed diametrically within the pump casing in sealed oscillatory contact with said pump casing and with the central portion of the baffle, said baffle and vanes respectively formed of double plates welded together, means for oscillating the vanes on the axis of the pump casing, said double wall baffle and pump casing defining a pair of fluid chambers, each of said chambers being divided into respective sets of displacement chambers by said diametrically disposed vanes, said double wall baffle including a pair of passageways connecting alternate displacement chambers in common, respective check valves controlling the flow of fluid relative to each of said displacement chambers, said check valves arranged in pairs relative to respective inlet and outlet passageways, one of said pairs of check valves being arranged to permit discharge of fluid and the other pair permitting intake of fluid, and said respective pairs of alternate displacement chambers operating alternately in common as simultaneous intake and discharge chambers as said impeller vanes are actuated in alternate directions.

4. In a pump having an inlet and outlet, a port and baffle unit mounted in fixed relationship to the inlet and outlet, a cylindrical pump casing disposed about said port and baffle unit with the port and baffle unit disposed diametrically within the casing to provide a pair of fluid chambers, a cup-shaped member including a vane assembly mounted for oscillation on the axis of said pump casing with the plane of the vane assembly bisecting the plane of said port and baffle unit and providing respective pairs of fluid displacement chambers, said pump casing being cup-shaped and nested with said cup-shaped member with their open ends extended inwardly, means for oscillating said assembly, said baffle unit including tubular portions extended parallel with the pump axis, valve means connecting the displacement chambers at either side of the baffle unit with said tubular portions of said baffle unit, respective tubular portions of said baffle unit being in communication with the inlet and outlet respectively for intake and discharge of fluid when the vane assembly is moved

within the chambers at either side of the baffle, and a pair of ports through said port and baffle unit communicating with alternate displacement chambers to permit intake and discharge of fluid simultaneously from respective pairs of displacement chambers through said tubular portions and valves to said inlet and outlet.

5. In a pump, a stationary manifold member including inlet and outlet openings, a cup-shaped casing fixed in relation to said member, a port and baffle unit fixed in relation to said manifold member diametric to said casing and defining a pair of fluid chambers, an actuator comprising a cup-shaped member nested within the pump casing with its open end disposed inwardly, said actuator including diametrically disposed vanes secured thereto, said vanes subdividing said fluid chambers into sets of displacement chambers, means for oscillating said cup-shaped member and vanes, means for sealing the vanes in relation to the port and baffle unit, said port and baffle unit including a cylindrical hub portion coaxial with the axis of the pump casing and having passageways connecting alternate displacement chambers in common, tubular portions at the outer ends of the port and baffle unit parallel with said axis and in communication with said inlet and outlet openings respectively, and respective check valves in said tubular portions for controlling the intake and discharge of liquid respectively through said openings.

6. In a pump, a baffle element consisting of a pair of sheet metal plates of duplicate form, said plates welded together to provide a cylindrical hub portion and tubular portions at the outer ends of the baffle parallel to said hub portion, a pump casing surrounding said baffle with the baffle disposed diametrically across said casing, defining a pair of fluid chambers, the casing having its axis coinciding with the axis of the hub of the baffle, respective intake and discharge valves located in respective tubular portions, said hub portion including a partition centrally thereof at right angles to the axis, ports at each side of the partition providing for flow of liquid diametrically through the hub at either side of the partition, said valves controlling the flow of liquid in the spaces at either side of the baffle to and from the respective outer tubular portions, impeller vanes disposed radially with respect to the said hub portion, said vanes dividing said fluid chambers into respective displacement chambers connected alternately in common through said ports, and means for oscillating the vanes on the axis of the hub for intake and discharge of liquid through the baffle and through said valves.

7. In a pump, a baffle element having a cylindrical hub portion and tubular portions at the outer ends of the baffle, a pump casing surrounding said baffle, said baffle extending diametrically with respect to said casing and defining a pair of fluid chambers, said hub portion including a partition centrally thereof at right angles to the axis, ports at each side of the partition providing for a flow of liquid diametrically through the hub at either side of the partition, respective intake and outlet valves in said tubular portions, said valves adapted for controlling the flow of liquid in the chambers at either side of the baffle to and from the respective outer tubular portions, inlet and outlet conduits in communication with the respective outer tubular portions, impeller vanes disposed radially with respect to the hub portion in

a plane bisecting the plane of said baffle comprising plates welded together and formed to provide slots along the inner edges of said vanes, seals in said slots engaging said hub, and means for oscillating the vanes on the axis of the hub for intake and discharge of liquid through the baffle and through said valves.

8. In a pump, a baffle providing a cylindrical hub and tubular outer portions disposed in parallelism with the hub, a pump casing surrounding said baffle with the baffle disposed diametrically thereto, said baffle defining a pair of fluid chambers, ports for controlling the flow of liquid from the chambers at either side of the baffle through the hub portion, impeller vanes disposed radially with respect to the hub portion in a plane bisecting the plane of said baffle to divide said fluid chambers into respective displacement chambers, said vanes formed of pairs of plates welded together in face to face contact, the inner ends of the plates spaced to provide slots for sealing members, sealing members in said slots engaging the tubular hub portion, said sealing members consisting of U-shaped flexible sheet metal members having outer arms in spring contact with the hub portion, intake and outlet means in communication with the respective outer tubular portions of the baffle, check valves in said tubular portions communicating respectively with said displacement chambers, and means for oscillating the vanes on the axis of the tubular hub portion.

9. In a pump, a baffle providing a cylindrical hub portion and tubular outer portions disposed in parallelism with the hub, a circular pump casing surrounding said baffle, with the baffle disposed diametrically thereto, said baffle defining a pair of fluid chambers, ports in said hub portion for providing a flow of liquid from the chambers at either side of the baffle through the hub portion, impeller vanes disposed radially with respect to the hub portion and in oscillatory sealing contact therewith, said vanes disposed in a plane bisecting the plane of said baffle to divide said fluid chambers into respective pairs of displacement chambers, said vanes formed of pairs of plates welded together, the inner ends of the plates formed to provide slots for sealing members, sealing members in said slots engaging the tubular hub portion, intake and outlet means in communication with the respective outer tubular portions of the baffle, check valves in said tubular portions communicating respectively with said displacement chambers, and means for oscillating the vanes on the axis of the tubular hub portion.

10. In a pump, a baffle element having a cylindrical hub portion and tubular portions at the outer ends of the baffle, a pump casing surrounding said baffle and having its axis coinciding with the axis of the hub of the baffle providing a pair of fluid chambers, said hub portion including a partition centrally thereof, ports at each side of the partition providing for flow of liquid diametrically through the hub at either side of the partition, valves controlling the flow of liquid from the chambers at either side of the baffle to and from the outer tubular portions, inlet and outlet conduits in communication with the respective outer tubular portions, and impeller vanes bisecting the plane of said baffle element and defining respective displacement chambers for causing intake and discharge of liquid through the baffle.

11. In a pump, a baffle consisting of a pair of sheet metal plates welded together to provide a cylindrical hub portion and tubular outer portions disposed in parallelism with the hub, a cir-

cular pump casing having its axis disposed on the axis of said hub portion and surrounding said baffle, said baffle being diametrically disposed with respect to said casing providing a pair of fluid chambers, means for controlling the flow of liquid to and from the chambers at either side of the baffle through the hub portion and into and out of respective outer tubular portions, impeller vanes disposed radially with respect to the hub portion and in oscillatory sealing contact therewith in a plane bisecting the plane of said baffle and defining respective pairs of fluid displacement chambers, said vanes formed of pairs of plates welded together in face to face contact, intake and outlet means in communication with the respective outer tubular portions of the baffle, and means for oscillating the vanes on the axis of the hub portion.

12. In a pump, a pump casing, a double wall baffle disposed diametrically within the pump casing and defining a pair of fluid chambers, said baffle providing passageways for the flow of liquid from one fluid chamber to the other, and including tubular portions having valves for receiving and discharging liquid endwise therefrom, intake and outlet means connected to the respective tubular portions, impeller vanes disposed diametrically within the pump casing in a plane bisecting the plane of said baffle and providing respective pairs of fluid displacement chambers and in sealed oscillatory contact with the pump casing and with the central portion of the baffle, said baffle and vanes respectively formed of duplicate plates welded together, and means for oscillating the vanes on the axis of the pump casing.

13. A pump comprising; a cup-shaped member mounted for oscillatory movement in a stationary casing, a stationary baffle structure extending diametrically across the inside of said cup-shaped member and defining a pair of fluid chambers therein, said baffle including a cylindrical hub portion with a partition therein disposed at right angles to the axis of the hub, diametrically disposed ports in the hub connecting said fluid chambers through the hub on each side of said partition, said baffle also having a pair of outer tubular portions disposed on either side of said hub and parallel thereto, one of said tubular portions having a valve controlled port opening into the interior of the tubular portion from each of said fluid chambers, the other tubular portion having a valve control port opening from the interior of the tubular portion into each of said fluid chambers, impeller vanes extending radially with respect to said hub and diametrical with respect to said cup-shaped member in a plane bisecting the plane of said baffle to provide respective pairs of fluid displacement chambers, said vanes fixed to said cup-shaped member at the outer ends and adapted for oscillatory engagement with said hub at their inner ends, and means for oscillating said vanes for displacing liquid relative to said baffle.

14. In a pump, a cup-shaped casing, a cup-shaped impeller element nested within said casing with its open end edge sealingly engaged against the closure wall of the casing, a fixed double wall structure disposed diametrically within said impeller element defining a pair of fluid chambers therein, said structure including inlet and delivery valve means for delivering liquid into said fluid chambers endwise thereof at one side of the center thereof and discharging it endwise at the other side of the center, said impeller element including vanes radially disposed

in a plane bisecting the plane of said double wall structure and defining respective pairs of displacement chambers, said vanes being fixed therein for oscillatory movement in the chambers at each side of the wall structure, means externally attached to the impeller for oscillating said impeller, and respective passageways through said double wall structure communicating with alternate displacement chambers to permit intake and discharge of fluid simultaneously from 10 respective sets of displacement chambers through said intake and delivery valves.
